Fig. 1

Fig. 2

Fig. 3

Fig. 4

FIGURE 1 is a side elevation of a stapler, showing my new design, the other side elevation being a mirror image thereof;

FIGURE 2 is an elevational view of the front end of the stapler;

FIGURE 3 is a similar view of the rear end of the stapler;

FIGURE 4 is a top plan view thereof;

FIG. 5 is a side elevation of another embodiment of the stapler shown in FIG. 1 with portions broken away and shown in section to better illustrate the panel-like recess on the top of the hand piece;

FIG. 6 is a top plan view thereof; and

FIG. 7 is a side and top perspective view thereof.

I claim:

The ornamental design for a stapler, as shown and described.
